US00D960874S

(12) **United States Design Patent** (10) Patent No.: **US D960,874 S**
(45) Date of Patent: **** Aug. 16, 2022**

(54) **MICROPHONE**

(71) Applicant: **Focusrite Audio Engineering Limited**,
High Wycombe (GB)

(72) Inventors: **Emma Claire Davies**, High Wycombe
(GB); **Simon Anthony Burges**,
Twickenham (GB); **Krischa Tobias**,
London (GB); **Peter Phillips**,
Milford-on-Sea (GB)

(73) Assignee: **Focusrite Audio Engineering Limited**,
High Wycombe (GB)

(**) Term: **15 Years**

(21) Appl. No.: **29/763,825**

(22) Filed: **Dec. 24, 2020**

(30) **Foreign Application Priority Data**

(57) **CLAIM**

The ornamental design for a microphone, as shown and described.

DESCRIPTION

FIG. 1 is a top perspective view of a microphone;
FIG. 2 is a left-side elevational view thereof, the right-side
view being a mirror image of the left side view;
FIG. 3 is a rear view thereof, the front view being a mirror
image of the rear view;
FIG. 4 is a top plan view thereof; and,
FIG. 5 is a bottom plan view thereof.

The broken lines in the drawings are provided to show
features or boundaries that form no part of the claimed
design.

1 Claim, 5 Drawing Sheets
